CLAIM

The ornamental design for a men's underwear with triple fly construction, as shown and described.

DESCRIPTION

FIG. 1 is a front view of a men's underwear with triple fly construction, showing the new design;
FIG. 2 is a right side view thereof;
FIG. 3 is a rear view thereof;
FIG. 4 is a top view thereof;
FIG. 5 is a bottom view thereof;
FIG. 6 is a top perspective view thereof;
FIG. 7 is a right perspective view thereof;
FIG. 8 is a rear perspective view thereof; and,
FIG. 9 is a front cross-sectional view thereof, wherein the cross-sectional view is taken along 9, shown in FIG. 4. The broken lines shown in the drawings represent portions of the men's underwear with triple fly construction that form no part of the claimed design.
